His Attorney.

UNITED STATES PATENT OFFICE.

JOHN B. FORD, OF SCHENECTADY, NEW YORK, ASSIGNOR TO GENERAL ELECTRIC COMPANY, A CORPORATION OF NEW YORK.

POLE SHADER.

Application filed June 22, 1921. Serial No. 479,600.

To all whom it may concern:

Be it known that I, JOHN B. FORD, a citizen of the United States, residing at Schenectady, county of Schenectady, State 5 of New York, have invented certain new and useful Improvements in Pole Shaders, of which the following is a specification.

It is common practice to provide pole shaders of copper or other good conducting 10 material for the purpose of setting up in a magnetic structure for alternating current apparatus, a magnetic flux which is displaced in phase from the main flux through the structure so as to thereby have 15 the flux in the structure maintained while the main flux is passing through the zero value. For example, such pole shaders have been used in alternating current switches to prevent chattering by setting up a 20 maintaining flux displaced in phase from the main flux, the maintaining flux serving to magnetically hold the movable magnetic member of the switch during the time while the alternations of the main flux pass 25 through the zero value. Such pole shaders have a disadvantage in that a substantial portion of the pole face of the magnetic structure must be cut away in order to accommodate the pole shader, and 30 the effective area of the pole face is thereby materially reduced since copper is non-magnetic.

One of the objects of my invention is to 35 provide a pole shader which is not only electrically conductive, but also has magnetic properties, so that the entire area of the pole face in which the pole shader is embedded shall be effective in carrying the lines of magnetic flux.

40 In order for the pole shader to have the greatest effect in setting up a displaced magnetic flux, the resistance of the pole shader should be approximately equal to the reactance thereof, and I have found that 45 steel has the desired properties, although my invention is not necessarily limited to pole shaders of steel.

The magnetic structure of an alternating current device is ordinarily made up of 50 laminations of magnetic material, and some means must be provided for holding the laminations together. Iron bolts or pins are customarily used for that purpose, since the iron bolts or pins are also magnetic.

Another of the objects of my invention is

to provide a pole shader which is held in place by the means for holding the laminations of the magnetic structure together. The pole shader is thereby securely held in place and becomes for all practical purposes 60 an integral part of the magnetic structure.

For a better understanding of my invention, reference is had to the accompanying drawing which shows an embodiment of my invention for purposes of illustration, 65 and in which Fig. 1 shows the operating electromagnet of an alternating current electromagnetic switch with two pole shaders incorporated therein, in accordance with my invention; Fig. 2 is a perspective detail 70 view showing one of the pole shaders in position on the pole face of the laminated magnetic core of the operating electromagnet; Fig. 3 is an exploded view of the arrangement shown in Fig. 2; and Fig. 4 75 shows an alternative method of mounting the pole shader on the polar surface of the laminated magnetic structure.

Referring to the drawings, the pole 80 shaders 10 and 11 are embedded in the pole surfaces of the laminated structure 12 of an operating electromagnet, having a winding 13 mounted on one of the poles of the magnetic structure. Associated with and forming a part of the magnetic structure is a 85 magnetic movable element, an armature 14, which is supported in a cradle 15 so that the armature will accurately align itself with the pole faces of the magnetic structure.

The cradle support 15 is pivotally 90 mounted in a support 16 and is adapted to operate a shaft 17 to which switch mechanism or other devices to be operated by the electromagnet are connected. While I have shown a pole shader on each pole of 95 the magnetic structure, my invention is not necessarily limited thereto, since a single pole shader will have beneficial results in maintaining the armature of the electromagnet attracted during the time that the main flux of the electromagnet is passing through the zero value. For switches in

100 which a cradled armature or other movable magnetic member is provided for cooperation with a U-shaped magnetic structure, I 105 find it advisable, although not necessary, to employ a pole shader embedded in the end of each leg of the magnetic structure. The pole shader is embedded in the laminated magnetic structure so as to be at right 110

- angles to the plane of the flux through the magnetic structure as is customary. By reference to Fig. 2 it will be observed that the main flat band part of the pole shader 10 is embedded in the laminated magnetic structure so that its outer surface is flush with the ends of the laminations of the magnetic structure. This pole shader is of magnetic and electric conducting material, and the resistance thereof is predetermined so as to be substantially equal to the reactance thereof. I have found that steel has the desirable quality of not only being magnetic, but also has a sufficiently high resistance so that the reactance of the pole shader will be substantially equal to the resistance. This pole shader will set up a magnetic flux which is angularly displaced with respect to the main flux set up in the magnetic structure due to the energization of the winding 13 so as to magnetically hold the armature 14 during the time that the main flux is passing through the zero value. By reason of the fact that the pole shader has a resistance which is substantially equal to the reactance thereof, the pole shader will have the maximum effect in setting up a suitably displaced magnetic maintaining flux.
- The pole shader is provided with angularly disposed ears 18 and 19 which embrace the sides of the pole and provide means for holding the pole shader in place in the magnetic structure. Each of the ears 18 and 19 is provided with an aperture through which the iron bolt or pin 20 is adapted to pass, so as to hold the pole shader in position in the magnetic structure, and also for the purpose of holding the laminations of the magnetic structure together. It will be seen that the effective area of the pole face of the magnetic structure has not been lessened in any way because of the provision of the pole shader. That is because of the fact that the pole shader is of magnetic material. It is also to be noted that the pole shader can be put in place on the pole of the magnetic structure and then filed so as to be exactly flush with the surface formed by the ends of the laminations of the magnetic structure. An accurate alignment of the armature 14 with respect to the surface of the magnetic structure is thereby made possible. The pole shader when in position on the pole of the magnetic structure becomes substantially an integral part of the magnetic structure.
- The pole shader is very effective in preventing the noise or chattering which occurs in alternating current devices. This is due to the fact that the pole shader sets up a very substantial dephased magnetic holding flux and also from the fact that the pole shader and the laminations are securely held together by the rivet or bolt 20.
- In Fig. 4, I have shown an alternative method of mounting the pole shader in position, and it will be seen that in this case the pole shader does not have the same proportion of the total of the pole surface included within the pole shader as in the case of the pole shaders of the other figures. The reactance of the pole shader in Fig. 4 will necessarily be less than the reactance of the pole shader as shown in Fig. 2. The resistance, however, will be the same and it will be understood from this by those skilled in the art the manner in which the pole shader may be adjusted in position so as to have the desired reactance. It will be understood by those skilled in the art the manner in which the resistance of the pole shader may be varied. The adjustment of the proper reactance for the pole shader will be determined by testing the effort required to pull the armature 14 away from the pole pieces.
- The ears 18 and 19 of the pole shader have a distinct effect in setting up the dephased magnetic flux. That is because of the fact that these ears, together with the pin 20, cause eddy currents to be set up in the magnetic pole and the flux set up by these eddy currents is also dephased from the main flux and thus assist dephased flux set up by the main flat part of the pole shader.
- In accordance with the provisions of the patent statutes, I have described the principle of operation of my invention, together with the apparatus which I now consider to represent the best embodiment thereof, but I desire to have it understood that the apparatus shown is only illustrative and that the invention can be carried out by other means.
- What I claim as new and desire to secure by Letters Patent of the United States, is,—
1. In combination, a magnetic structure having a winding thereon and a pole shader in the pole face of said structure, the said pole shader having a resistance which is substantially equal to the reactance thereof.
  2. A pole shader having a main part consisting of a band having ears on the ends thereof angularly disposed to the said main part for embracing the sides of a pole of magnetic material to hold the pole shader in position on the pole.
  3. In combination, a magnetic structure, and a pole shader thereon having a main part consisting of a band and an ear on each end thereof angularly disposed to the said main part for embracing the sides of the pole of the said magnetic structure, the said ears having apertures therein, and a pin of magnetic material which passes through the said ears and the said magnetic structure for holding the pole shader in position on the pole and for setting up a dephased magnetic flux which assists the dephased flux of the said main part of the pole shader.

4. The combination in an electromagnetic device of a magnetic structure comprising a core and a movable member arranged to be magnetically attracted into engagement with a pole surface of the said core, and a steel pole shader embedded in the said structure and forming a part of the engaging surfaces of the said member and core, the said pole shader having a resistance which is substantially equal to the reactance thereof.

5. The combination in an electromagnetic device of a laminated magnetic structure, a steel pole shader, having a resistance substan-

tially equal to the reactance thereof, embedded in and surrounding a portion of the pole surface of said structure, the said pole shader having angularly disposed ears on the ends thereof which embrace the sides of the pole, the said ears having apertures therein, and a bolt which passes through the said apertures for holding the pole shader in position on the said pole and for holding the laminations of said structure together.

In witness whereof, I have hereunto set my hand this 21st day of June, 1921.

JOHN B. FORD.
